Primary Examiner — Philip S Hyder**CLAIM**

An ornamental design for a reach extender, as shown and featured in the accompanying drawings.

DESCRIPTION

FIG. 1 is a right, back, top perspective view of a reach extender in accordance with the present invention;

FIG. 2 is a left, front top perspective view of a handle portion of the reach extender;

FIG. 3 is a top, right, back perspective of the head portion of the reach extender;

FIG. 4 is a back elevation view thereof;

FIG. 5 is a front elevation view thereof;

FIG. 6 is a right elevation view thereof; and,

FIG. 7 is a top plan view thereof.

The right and left sides of the head portion of the reach extender are identical. The top and bottom sides of the head portion of the reach extender are also identical.

The broken lines represent portions of the structure that form no part of the claim.

1 Claim, 7 Drawing Sheets
